CLAIM

The ornamental design for a cart for transporting mattress or the like, as shown and described.

DESCRIPTION

FIG. 1 is a perspective view of the cart for transporting mattress or the like showing my new design;

FIG. 2 is a top plan view thereof;

FIG. 3 is a bottom plan view thereof;

FIG. 4 is a side elevational view thereof, the opposite side being a mirror image of that shown;

FIG. 5 is a front elevational view thereof; and

FIG. 6 is a rear elevational view thereof.
